BIRD FEEDER

Leonard Onos, 88 Ramapo Hills Blvd.,
Oakland, N.J. 07436

Filed Oct. 27, 1971, Ser. No. 193,234

Term of patent 14 years

Int. Cl. D30—03

U.S. Cl. D30—13

FIG. 1

FIG. 2

FIG. 3

FIG. 1 is an isometric view of a bird feeder of my new design;

FIG. 2 is an elevation view of one end of the bird feeder of FIG. 1, the other end being the same; and

FIG. 3 is an elevation view of one side of the bird feeder of FIG. 1, the other side being the same.

I claim:

The ornamental design for a bird feeder, substantially as shown and described.
